UNITED STATES PATENT OFFICE.

ARTHUR K. MILLER, OF PEEKSKILL, NEW YORK.

DESIGN FOR A GAS-BURNER PILLAR.

No. 38,961.

Specification for Design.

Patented Dec. 24, 1907.

Application filed October 17, 1907. Serial No. 397,940. Term of patent 7 years.

To all whom it may concern:

Be it known that I, ARTHUR K. MILLER, a citizen of the United States, residing in the city of Peekskill, in the county of Westchester, in the State of New York, have invented a new, original, and ornamental Design for a Gas-Burner Pillar, of which the following is a specification, reference being had to the accompanying drawing, forming part thereof, and in which—

Figure 1 is a side view showing gas burner pillar incorporating my design; and Fig. 2 is a top view thereof.

I claim:

The ornamental design for a gas burner pillar, as shown.

ARTHUR K. MILLER.
